UNITED STATES PATENT OFFICE.

FRANK H. WHEELOCK, OF WASHINGTON, DISTRICT OF COLUMBIA.

SELF-HEATING SAD-IRON.

1,070,645.

Specification of Letters Patent. Patented Aug. 19, 1913.

Application filed June 10, 1912. Serial No. 702,721.

To all whom it may concern:

Be it known that I, FRANK H. WHEELOCK, a citizen of the United States, residing at Washington, District of Columbia, have invented certain new and useful Improvements in Self-Heating Sad-Irons; and I do hereby declare the following to be a full, clear, and exact description of the invention, such as will enable others skilled in the art to which it appertains to make and use the same.

My invention relates to new and useful improvements in self heating sad-irons and more particularly to that class in which gas or similar combustible material is used for fuel and my object is to provide a very simple and durable form of burner and one wherein thorough distribution of heat is produced.

A further object is to provide means for causing the flame or products of combustion from the burner to travel through the combustion chamber in a substantially spiral path.

Other objects and advantages will be hereinafter set forth and pointed out in the following specification.

In the accompanying drawings which are made a part of this application, Figure 1 is a longitudinal central sectional view through the burner showing the same applied to use in connection with an iron. Fig. 2 is a transverse sectional view through the iron showing the burner in end elevation. Fig. 3 is a perspective view of the burner and the part to which it is attached, and, Fig. 4 is a top plan view of the combustion chamber removed from the iron.

Referring to the drawings in which similar reference numerals designate corresponding parts throughout the several views, 1 indicates an iron which may be constructed in the usual or any preferred manner, such as is used for ironing clothes and other garments and 2 indicates the combustion chamber which is located within the hollow of the iron, the roof 3 of the combustion chamber being preferably curved as shown for a purpose to be hereinafter set forth. The combustion chamber is spaced from the walls of the iron and is open at each end, while the lower edges are provided with elongated slots 4 so that the heat can escape between the floor of the iron and the lower edges of the combustion chamber and readily circulate between the combustion chamber and walls of the iron.

The combustion chamber is held in position within the iron by extending a screw 5 downwardly through the top of the iron and into engagement with the top of the combustion chamber, said screw clamping the combustion chamber against the floor of the iron. The forward end of the combustion chamber is likewise provided with an extension 6, which is curved to fit the curved end of the iron, said extension serving to better scatter the flame or products of combustion and direct the same against the floor and walls of the forward portion of the iron.

The rear end of the iron is provided with a door 7, which is hinged at its upper edge to the iron and when in closed position, the lower edge of the door engages a stop 8 fixed to the bottom of the iron. Extending substantially centrally through the door is a tube or mixing chamber 9, to the inner end of which is attached my improved form of burner 10, said burner being substantially a hollow cup-shaped member which fits over the end of the tube and has its inner end in engagement with the inner face of the door, while a lock nut 11 is placed around the tube 9 and engages the outer face of the door, thus securely locking the burner and tube in engagement therewith. The weight of the tube 9 and the parts attached thereto, serve to keep the door 7 closed while the iron is in use.

The peripheral edge between the end wall 12 and the side wall 13 of the burner is beveled, as best shown at 14, and through this portion of the burner are formed a plurality of openings 15, said openings extending at right angles to the beveled portion 14 and preferably arranged eccentric to the axis of the burner. The end wall 12 is likewise provided with a plurality of openings 16, which are inclined outwardly from the axis of the burner and also eccentrically thereto and by arranging the openings 15 and 16 in this manner and directing the inclination thereof in the same direction, the flame or products of combustion from the burner will be caused to travel in a spiral path through the combustion chamber, thus obtaining the full product of heat from the flame while traveling through the combustion chamber and by curving the roof 3 in the manner shown, said roof will not interfere with the spiral movement of the products of combustion.

The openings 15 and 16 are so arranged that the jets of flame will freely commingle

after passing from the burner and travel in the same general path, thus avoiding any possibility of creating a pocket between the sets of flame which would tend to form monoxid or other objectionable gases or odors.

The gas or other fuel is conducted into the mixing chamber 9 in any suitable manner, but in this instance I have shown a flexible tube 17 and in order to provide a proper amount of air for mixing with the gas, the tube 9 is provided adjacent its outer end with a number of ports 18 and owing to the suction caused by the fuel passing through the tube, the air will be readily drawn through said ports and properly mixed with the gas while passing through the mixing chamber.

The door 7 has its lower corners cut away to form inlet openings 19, through which air may pass into the interior of the iron, while the side walls of the iron are provided with outlet openings or slots 20, through which the used products of combustion may escape from the interior of the iron.

In lighting the burner when attached in the manner shown, it is but necessary to swing the door upwardly, which will expose the end of the burner and by turning on the gas and applying a match thereto, it can be very easily lighted. It will likewise be seen that in view of the simplicity of the burner, it can be very cheaply manufactured and readily applied to use and, while I have shown the same in the present instance as used for heating an iron, it will be readily understood that it can be used for heating other objects by introducing the burner into a combustion chamber and it will further be seen that by arranging the openings in the burner in the manner shown the products of combustion will travel in a spiral path, thus obtaining a better distribution of the heat.

What I claim is:

1. A burner comprising a hollow body having one end closed, said burner having a

plurality of openings extending therethrough at the meeting edge between the side and end walls of the burner, said end wall also having a plurality of openings extending therethrough, all of said openings being inclined in the same direction and eccentrically to the axial center of the burner. 55

2. A hollow burner having one of its ends closed, the meeting edge between said closed end and side wall of the burner being beveled, said beveled portion having a plurality of openings extending therethrough, said end wall also having a plurality of openings, all of said openings being eccentrically disposed to the axial center of the burner, and means to convey fuel into said burner. 60

3. The combination with a hollow-like burner having one of its ends closed, series of openings through the end and at the junction of the side and end walls of said burner, said openings being arranged eccentrically of the axis of the burner, a mixing chamber attached to the burner and a combustion chamber into which the products of combustion pass from the burner. 70

4. The combination with a hollow iron, a door hinged to one end of the iron and a combustion chamber within the iron and spaced from the walls thereof, said combustion chamber having a curved roof and an extension at one end thereof, of a mixing chamber extending through the door, a hollow burner attached to the mixing chamber and within the iron, said burner having a plurality of openings therethrough arranged eccentrically to the axis of the burner whereby the flame from the burner will be caused to travel in a spiral path through the combustion chamber. 80

In testimony whereof I have signed my name to this specification in the presence of 90 two subscribing witnesses.

FRANK H. WHEELOCK.
